UNITED STATES PATENT OFFICE.

RUSSELL C. MELLING, OF KENT, OHIO.

PAPER-ROLL HOLDER.

Application filed March 31, 1927. Serial No. 179,907.

This invention relates to paper roll holders and more particularly to a device for supporting rolls of toilet paper.

An important object of the invention is to produce a device of this character upon which the paper roll may be very readily mounted and from which the paper roll is unremovable until the paper has been entirely removed therefrom.

10 A further object of the invention is to produce a device of this character which, in addition to functioning as a support for roll paper, may also serve as a bumper for limiting opening movement of a door.

15 A still further object of the invention is to produce a device of this character which may be readily and cheaply constructed, which will be durable and efficient in service and a general improvement in the art.

20 These and other objects I attain by the construction shown in the accompanying drawing, wherein for the purpose of illustration is shown a preferred embodiment of my invention and wherein:—

25 Figure 1 is a side elevation of a roll paper holder constructed in accordance with my invention, a paper roll core partially broken away being shown in position thereon and the paper roll being indicated by dotted lines;

30 Figure 2 is a view similar to that of Figure 1, in which portions of the roll are broken away to show the interior construction and the roll core is shown as partially removed in solid lines and as substantially completely removed in dotted lines and retaining elements for this core are illustrated in their corresponding position;

35 Figure 3 is a section on the line 3—3 of Figure 1;

40 Figure 4 is a section on the line 4—4 of Figure 2.

Broadly considered, my invention comprises a rotatable supporting shaft 10 having one or more spring fingers 11 associated therewith. The roll 10 is of a size to approximately fit the interior of the tubular core 12 of a paper roll 13 and the spring finger or fingers 11 are so constructed that they normally resist application of this core thereto and accordingly when the core is in applied position, press outwardly against the inner wall of the core and tend to imbed themselves in the

55 relatively soft material thereof. The resistance of the core supplied by the backing or paper roll 13 is sufficient to prevent penetration of these spring fingers to an extent where the core may be removed. When, however, the roll is removed and the core 60 grasped firmly with the hand and drawn outwardly, the ends of these fingers 11 will penetrate the material of the core, permitting the fingers to be revolved about their points of attachment until they assume a 65 position opposed to that in which they occupy when the core is first applied and permit the core to be readily removed.

The shaft 10 is preferably formed with an axial bore 14, which is reduced adjacent the inner end of the shaft to provide an outwardly facing shoulder 15. This shoulder receives a projecting head 16 formed on a pivot bolt 17, which fits the reduced portion 70 of the bore and has its inner end threaded into a plate 18, which is provided with suitable means for attaching the same to a wall of the lavatory. The outer face of this plate preferably has a frusto-conical enlargement 75 19, increasing the bearing surface between 80 the roll and plate and providing a boss or thickening of the plate for the formation of a threaded bore 20, for the reception of the inner end of the pivot bolt. The outer end of the shaft preferably has applied thereto 85 a rubber bumper 21, the inner face of which has a plug 22 frictionally engaging in the outer end of the bore 14.

Extending diametrically of the shaft, intermediate the ends thereof, is a bore 23, 90 which, at its opposite ends, communicates with recesses 24. The inner walls of the recesses 24 extend in opposite directions from the bore 23 and are parallel to one another. The side walls 25 of the recesses diverge 95 from the bore 23. The shaft at one side of the bore is transversely slotted, as at 26, with a slot communicating at its inner end with the bore 23. Within the bore is arranged a coil spring 27, the ends of which are extended to provide the arms 11. These extensions, in the normal position thereof, are preferably at 180° to one another and the arms are of such length that when either arm is flexed about its coil for the maximum distance, its terminal portion will project slightly beyond the periphery of the shaft. By inspecting Figure 2, it will become ob-

vious that by flexing the lower arm 11 until it parallels the upper arm 11, this arm will be brought into alignment with the slot 26 and may be shifted therethrough to permit insertion or removal of the spring 27.

Since the spring 27 is free to rotate within the bore 23, it will be obvious that one or the other of the arms 11 will normally incline toward the outer end of the shaft.

As the paper roll is applied thereto, it will come in contact with this arm and the arm will move before it until both arms are in contact with the end of the core 12. Continued movement of the roll in a direction to apply the same will cause the arms 11 to flex toward the rear side walls 25 of the recesses 24. This will obviously place the spring 27 under tension and accordingly when the roll is fully applied, the ends of the arms will tend to embed themselves in the material of the core 12, as more clearly shown in Figures 1 and 2. After the paper has been entirely removed from the roll, the outer end of the core may be grasped with the hand and moved outwardly. The ends of the arms 11 being embedded in the core, will force their way therethrough and as these arms come into alignment, they will occupy a position substantially as shown in full lines in Figure 2. As the movement of the core continues, the arms will be flexed in the opposite direction until they occupy the position shown in dotted lines in this figure and in this position, they will remain until the core is entirely withdrawn. With the withdrawal of the core, they will be returned to their normal position which is that indicated in dotted lines in Figure 2.

Since it will be obvious that the construction hereinbefore set forth is capable of a certain range of change and modification without materially departing from the spirit of the invention, I do not limit myself to such specific structure except as hereinafter claimed.

I claim:—

1. In a roll paper holder and in combination, a rotatable supporting shaft adapted to receive and interiorly fit a paper roll having a core therein, means yieldably resisting application of a paper roll to the shaft and after application of the paper roll thereto having engagement with the core of the roll

55 preventing withdrawal thereof until said means has pierced the core of the roll.

2. In a roll paper holder and in combination, a rotatable supporting shaft adapted to receive and interiorly fit a paper roll having a core therein, a finger associated with the shaft and swingable from a position where it extends transversely of the shaft to positions at opposite sides of the first named position where it substantially aligns with the shaft, the free end of said finger in each of the last named positions having its extremity extended slightly beyond the surface of the shaft for engagement with the core of the paper roll and when in the first named position projecting considerably beyond the surface of the roll whereby in order to permit removal of the paper roll core from the shaft said finger must pierce the wall of the core.

3. In a roll paper holder and in combination, a rotatable supporting shaft adapted to receive and interiorly fit a paper roll having a core therein, a finger associated with the shaft and swingable from a position where it extends transversely of the shaft to positions at opposite sides of the first named position where it substantially aligns with the shaft, the free end of said finger in each of the last named positions having its extremity extended slightly beyond the surface of the shaft for engagement with the core of the paper roll and when in the first named position projecting considerably beyond the surface of the roll whereby in order to permit removal of the paper roll core from the shaft said finger must pierce the wall of the core, and means constantly urging said finger into engagement with the inner wall of the core of a roll of paper applied to the shaft.

4. In combination, a rotatable shaft having a transverse bore, a coil spring within the bore, the outer ends of the bore communicating with recesses oppositely directed from the bore transversely of the shaft, the terminal portions of the spring being extended to produce arms disposed at an angle of approximately 180° to one another and operating in said recesses.

In testimony whereof I hereunto affix my signature.

RUSSELL C. MELLING.
